UNITED STATES PATENT OFFICE.

JOSEPH WACKERMAN, OF WARREN, PENNSYLVANIA.

SNOW-PLOW.

SPECIFICATION forming part of Letters Patent No. 325,029, dated August 25, 1885.

Application filed February 5, 1885. (No model.)

To all whom it may concern:

Be it known that I, JOSEPH WACKERMAN, of Warren, in the county of Warren and State of Pennsylvania, have invented a new and 5 Improved Snow-Plow, of which the following is a full, clear, and exact description.

My invention relates to snow-plows adapted especially for use in clearing railway-tracks, and has for its object to provide a machine the 10 snow-shovels of which have freedom of movement in rounding curves of the track, and may be raised or lowered as required and adjusted to the tracks for clearing them effectively and quickly. The invention may also be used for 15 clearing paths over common roads.

The invention consists in particular constructions and combinations of parts of the snow-plow, all as hereinafter fully described and claimed.

Reference is to be had to the accompanying drawings, forming part of this specification, in which similar letters of reference indicate corresponding parts in all the figures.

Figure 1 is a plan view of my improved 25 snow-plow as attached to a locomotive-engine for clearing the railroad-tracks. Fig. 2 is a side elevation of the same. Fig. 3 is a sectional side elevation of the same. Fig. 4 is an under side view of the snow-plow, and Figs. 5 30 and 6 are detail side views of a couple of the runners of the plow.

I make the snow-plow with the concave mold-boards A A joined at their forward ends and diverging backward, and secured to a 35 bed-plate or platform, B, which inclines downward and forward, and has a square end extending forward to the letter b, Figs. 2, 3, and 4. The parts A B are supported by a frame, A', of wood or iron bars, which may connect 40 the plow to the front of a locomotive-engine, B', for clearing the tracks C of snow; or the plow may be supported in front of a traction-engine or wheeled vehicle for use on common roads.

The letter D indicates a frame or plate, to 45 which are connected the snow-shovel plates E F. The shovel-plate E is bolted rigidly to the rear part or bar, d, of the frame D, and so that its rear edge overlaps the forward end, b, of 50 the bed-plate B; and the shovel-plate F, which in a railway snow-plow is made preferably in three sections, is hinged at e to the

front edge of the plate E, and rests on the front bar, d', of the frame D.

To the rear bar, d, of the frame D are fixed 55 a series of arms, d'', which project backward and are rabbeted, so as to give space for the forward end of the bed-plate B between them and the overlapping rear edge of the shovel-plate E; and to the arms d'' is fixed a curved 60 bar, G, which bears against the guide and anti-friction rollers H; or it may be grooved guide-blocks journaled or fixed to the bed-plate B.

With this construction the shovel-plates E 65 F and frame D are supported by the bed-plate B, and are at liberty to turn bodily to either side as the bar G moves over the rollers H, to allow the machine to turn curves more readily 70 without damage to the plow-runners, presently described.

The letter I indicates a transversely-ranging shaft, which is journaled in the mold-board A or hangers thereon, and has a lug or lugs at i, to which is pivoted the upper end of a bar or 7 rod, J, the lower end of which is pivoted at j to the rear end of a longitudinally-ranging bar, K, which is fulcrumed at k in a post, L, fixed to the under side of the bed-plate B.

The bar K extends forward into a box or 80 casing, M, which is fixed to the under side of the frame D, and is sufficiently wide to allow lateral play of the frame D and plow-shovel plates E F without striking the end of bar K, and the extreme end of the bar K is 85 so fitted to the box M that when the shaft I is rocked to depress the back end of bar K its forward end will lift the frame D and shovel-plates E F and the forward ends of the plow-runners O O', the back edge of plate E 90 then sliding rearward more or less on the bed-plate B.

For operating the shaft I to raise or lower the shovel-plates and runners, I provide a 95 rod or bar, N, which is connected with an arm or lug, n, fixed to the shaft, and extends rearward to the engine-cab, or within reach of an attendant on a vehicle to which the snow-plow may be attached. Arms n', having adjustable weights n'', are fixed to the shaft I and partly 100 counterbalance the weight of the shovel-plates and runners, and allow them to be more easily lifted by the rod N.

Links or rings p on the ends of a yoke, P,

connect it loosely to the curved bar G, and a loop or eye, p' , formed in or fixed to the center of the yoke connects it loosely with the fulcrum-post L of the shovel-adjusting bar K. 5 The yoke P allows free lateral and curving movements of the shovel plates and runners, and prevents their disconnection in a forward direction from the bed-plate B and mold-board of the plow.

10 I pivotally connect the forward ends of the runners O O' to the front edge of the shovel-plate F by means of pins o, which pass through lugs o', fixed to the runners, and lugs o'', fixed to the shovel-plate; and the rear ends of the

15 runners have slots R, through which passes a transversely-ranging bar or rod, S, which is held at the ends in hangers T, fixed to the bed-plate B, and two or more intermediate brace-rods, t t, may connect the bar S to the

20 bed-plate, if desired. One or more of the central runners, as at O', Fig. 6, have their slots R open to their back ends, which allows

25 these runners to be removed by taking out their front pivots, o, and slipping them forward off the bar S, as may sometimes be necessary when the ballast is high at the center of the track.

To the outer end or edge of the forward shovel-plate, F, and at points between the runners O O', are fixed the upwardly-curved guard-bars U, which serve to lift the shovels above any obstacles which may chance to lie in the path of the plow between the runners, and which would not be struck by the runners.

30 35 Slots or openings V are made in the forward edge of the shovel plate F, into which slots the railway tracks C enter as the plow moves forward.

As before stated, I make the shovel-plate F 40 in sections, three sections being shown—viz., a central section, F', and two opposite end sections, F² F². This construction allows the central and end runners, O O', of each section F' F² to swing independently forward on the bar S and upward on the hinges e, as the various runners meet inequalities of ground or tie surface along the track or road; and to allow the outside runners to be lifted higher at the forward ends than the inner runners, so as to meet 45 and pass over considerable inequalities on the ends of the ties, and also to allow vertical adjustment of the end sections, F², above the central shovel-section, F', when it is not desired to cut down the snow quite so close to the ties at 50 the outside of the rails, I make the shovel-sections F² with two plates, f² f²—the one f² hinged at e to the shovel-plate F, and the one f² held to the plate f² by screws f⁴, passed through slots in plate f³ into plate f², so that 55 by loosening screws f⁴ the plates f³—to which the outer runners, O, and guards U are attached—may be raised or lowered at any time, as will readily be understood.

I provide cutters, as at W, which are fixed 60 at the opposite ends of the central shovel-plate section, F', and serve to make a clean

cut through the snow along the tops of the rails C C, and facilitate the clearing of them by the plow.

When the plow is intended for use on common roads, the shovel-plate F may be made in one piece and without the slots V and cutters W; or said plate F may be made in the three sections F' F² F², with the outer sections, F², in one piece and with or without 75 the cutters W, as may be desired, the construction of the shovel-plates, as hereinbefore described, being intended more especially for plows to be used in clearing railway-tracks. 80

It is obvious that when the snow-plow is at work the runners O O' will be raised when running over crossings or switches of the railway-track, and the runners will raise the shovel-plate F clear of the tracks. 85

When the plate F is lifted by the runners, the snow beneath the plate will have a chance to escape freely through the frame D by passing over its front bar, d', and beneath the plate E and the rear bar, d'', of the frame; 90 hence the snow will not pack at the front of the plow beneath the shovel-plates when the outer plate, F, is lifted, and when the plate falls again it will have a solid support on the cross-bar d' of frame D against the pressure 95 of the snow lifted by it, and the snow passes backward over the bed-plate B, and is thrown sidewise both ways by the mold-boards A, which, however, may be shaped to throw all the snow to either side of the track. 100

By taking out the bar S and detaching the ends of yoke P from the curved bar G the runners and shovel-plates may be removed from the plow for adjustment, repair, or renewal when required. 105

Having thus described my invention, what I claim as new, and desire to secure by Letters Patent, is—

1. A snow-plow constructed with a laterally-movable and vertically-adjustable shovel-plate at its forward end, and with means for raising and lowering the plate, substantially as herein set forth. 110

2. A snow-plow constructed with a laterally-movable shovel at its forward end, which 115 overlaps the bed-plate of the plow, and said shovel being made in two plate-sections hinged to each other crosswise of the plow, substantially as herein set forth.

3. A snow-plow constructed with a laterally-movable shovel at its forward end, and said shovel overlapping the bed-plate of the plow, and made in two plate-sections hinged to each other crosswise of the plow, and the front shovel-plate having runners pivoted to it, and 120 said runners having a longitudinal slot-connection with a rear cross-bar fixed to the plow bed-plate, substantially as herein set forth. 125

4. A snow-plow constructed with a laterally-movable shovel at its forward end, which 130 shovel overlaps the plow bed-plate, and is made in two plate-sections hinged to each

other crosswise of the plow, and the front shovel-plate being made in central and opposite end parts independently movable vertically on their hinge-joints, and with runners 5 pivoted near their forward ends to the front shovel-plate sections, and having a longitudinal slot-connection at their rear ends with a cross-bar fixed to the plow bed-plate, substantially as herein set forth.

5. The combination, in a snow-plow, of the mold-board and bed-plate A B, the shovel-plates E F, hinged together at e, the plate E overlapping bed-plate B, and being fixed to a frame, D, which has backwardly-projecting 15 arms d², the curved bar G, fixed to bed-plate B, and against which the bar G presses, the links p and yoke P, connecting bar G with a post fixed to the bed-plate, and means for raising or lowering shovel-plates E F and frame D, 20 substantially as herein set forth.

6. The combination, in a snow-plow, of the mold-board and bed-plate A B, the shovel-plates E F, hinged together at e, said plate E overlapping the plate B, and being fixed to a frame, D, which has arms d², the bar G, sheaves or guides H, the yoke P, links p, connecting the bar G and the shovel-plates to a post on bed-plate B, and the lever K, fulcrumed on a post, L, fixed to plate B, and said 25 lever extending forward beneath the shovel-plate frame D, to raise and lower the shovel-plates, and means for operating the lever, substantially as herein set forth.

7. The combination, in a snow-plow, of the mold-board and bed-plate A B, shovel-plates E F, hinged together at e, and said plate E overlapping bed-plate B, and being fixed to a frame, D, which has arms d², the bar G, sheaves or guides H, the yoke P and links p, connecting the bar G and the shovel-plates E F to a post on bed-plate B, the lever K, fulcrumed on post L and extending into a casing, M, fixed to frame D, the bar J, shaft I, arm n, and the rod N, extending to the attendant behind the 40 plow, substantially as herein set forth.

8. The combination, in a snow-plow, and with the hinged shovel-plate E and frame D, supported from the bed-plate B, so as to have lateral and vertical movements, substantially 45 as described, of the plate F, having openings V V for the railway-tracks to enter, substantially as herein set forth.

9. The combination, in a snow-plow, and with the hinged shovel-plates E F and frame 50 D, supported from the bed-plate B, so as to have lateral and vertical movements, substan-

tially as described, of runners O O', pivoted at o to the shovel-plate F, and connected by slots R at their back ends with a cross-bar, S, held in posts T, fixed to the bed-plate B, substantially as herein set forth. 60

10. The combination, in a snow-plow, and with the hinged front shovel-plate, F, of the central runner or runners, pivoted at o to the plate F, and having open slots R at their back 65 ends, substantially as herein set forth.

11. In a snow-plow, the shovel-plates E F, hinged together at e, and supported on a frame, D, and from the bed-plate B, so as to have lateral and vertical movements, substantially 70 as described, and said plate F being made in sections F' F² F³, to which the forward ends of the runners O O' are pivoted, substantially as herein set forth.

12. In a snow-plow, the shovel-plates E F, 75 hinged together at e, and supported on a frame, D, and from the bed-plate B, so as to have lateral and vertical movements, substantially as described, and said plate F being made in sections F' F² F³, and the sections F² consisting of plates f², hinged at e to shovel-plate E, and plates f³, having the runners O pivoted to them, and held so as to be adjustable over the plates f², substantially as herein set forth. 80

13. In a snow-plow, the shovel-plates E F, 85 hinged together at e, and supported from the bed-plate B and on a frame, D, made with a rear bar, d, and with a front bar, d', on which the plate F rests, and over which bar d' the snow passes when the plate F is lifted by the 90 runners, which are pivoted to the plate at their forward ends, substantially as herein set forth.

14. In a snow-plow, the shovel-plates E F, hinged to each other at e, and supported from the bed-plate B and on a frame, D, in combination with runners pivoted at o to the plate F, and said plate F being made in sections F' F² F³, and having openings V V for the railway-tracks at the meeting ends of its sections, and cutters W W, secured to the section F' at 95 100 the openings V V, substantially as herein set forth.

15. In a snow-plow, the combination, with the hinged shovel-plate F and runners O O', pivoted thereto, of the upturned guards U, 105 fixed to the shovel-plate between and next the runners, substantially as herein set forth.

JOSEPH WACKERMAN.
